DRUM STRUCTURE FOR RING AND ROLL MILLS

Robert F. Dore, Los Angeles, and George L. Chrisope, Glendale, Calif.

Application September 17, 1945; Serial No. 616,662

5 Claims. (Cl. 241—91)

1

This invention relates to a drum structure for a ring and roll mill.

An object of the invention is the provision of a drum structure for a ring and roll mill which will grind ore in such a manner that classification of the ore is eliminated.

The mill of the present invention utilizes an assemblage of equal diameter grinding rings to form a drum. An object of the invention is to provide a construction whereby the grinding rings may be maintained on a common axis and positively held against shifting in a plane transverse to the ring axis or along the ring axis.

With respect to the aforementioned object, it is essential that the rings be maintained uniformly spaced apart, to the end that the fines are of a predetermined size.

A further object consists in a construction whereby the grinding rings may be rapidly assembled or dismantled.

A further object is the provision of means adapted to readily permit the separation of mill ends in a mill of the character stated.

A further feature of the invention resides in a novel means for spacing the grinding rings.

Further objects include a device which is simple of structure, inexpensive in cost to manufacture, and superior to mills now known to the inventor.

With the above mentioned and other objects in view, the invention contemplates the novel and useful provision, formation, construction, association and relative arrangement of parts, members and features all as shown in the drawings, described generally in the specification and more particularly pointed out in the claims.

In the drawings:

Fig. 1 is a fragmentary and sectional elevation of the improved mill;

Fig. 2 is a sectional view on the line 2—2 of Fig. 1;

Fig. 3 is an enlarged fragmentary sectional view on the line 3—3 of Fig. 2;

Fig. 4 is a fragmentary section on the line 4—4 of Fig. 3;

Fig. 5 is a perspective view of one of the shim members;

Fig. 6 is a perspective view of one of the grinding rings;

Fig. 7 is an enlarged fragmentary sectional view on the line 7—7 of Fig. 2; and,

Fig. 8 is a perspective view of one of the ties used in the practice of the invention.

Referring now to the drawings:

We have illustrated in Fig. 1 a mill illustrating the invention and wherein is provided ends

1 and 2, between which is positioned grinding rings 3 of the character shown in Fig. 6. These rings are all on the same axis and of the same diameter and construction. It is intended that the rings should be spaced apart to permit the fines to pass between the rings for peripheral discharge. Ordinarily, an assembly of rings as shown in Fig. 1 interposed between ends 1 and 2 is termed a drum, and within the said drum and adapted to rest upon the rings transversely thereof is positioned one or more elongated rollers of selected weight (see Fig. 2). The rollers are adapted to roll and slide over the ore received within the drum for the purpose of grinding the same to a size sufficient to permit the discharge thereof between the rings. The drum is adapted to be rotated by some external means, and to this end the drum is suitably supported upon an axial tubular shaft 4. The tubular shaft in turn is carried in bearing blocks 5 and 6, which are mounted upon suitable supports adapted to carry the weight of the drum. The supporting structure is shown at 7 and includes end members 8 and 9 with interconnecting transverse bracing 10. As shown in Fig. 7, the end 1, as likewise the end 2, rotates with the shaft by being keyed diametrically thereto, as indicated at 11.

The present invention is primarily directed to

a mill of the character just briefly described incorporating a new construction of grinding ring 3 adapted to be locked in position of service between the mill ends, together with novel means for spacing the grinding rings apart. The invention likewise contemplates means whereby the mill ends may be separated or caused to approach.

Adapted to extend between the mill ends 1 and 2 and adjacent the rims thereof are ties of the type shown in Fig. 8, designated as an entirety by 12. These ties are spacedly arranged in substantial parallelism between the mill ends. Each tie includes an elongated body carrying at each end pairs of spaced apart, screw-threaded studs 13 and 14 for one end, and 15 and 16 for the other end. These threaded studs may be conveniently held within the tie by providing the tie with screw-threaded bores, as shown for instance in Fig. 3, at 17. It is intended that each tie should be so mounted between the mill ends as to be capable of swinging movement on the threaded studs 13 and 16. It may thus be said that the elongated tie is one form of swing arm of extended width and short length. The portion of the tie that carries the studs 14 and 15 is provided with an elongated and rounded flange or tongue 18. Diametrically opposite the flange or

tongue 18 is a web 19, which may vary as to depth between ends of the tie, best shown in Fig. 8. The web is provided for the purpose of preventing any bending movement of the tie in the plane of the tongue or flange 18. If the size of the mill has been selected and the spacing between the mill ends is known, ties of a given length will be provided, the threaded studs 13 and 16 passed through openings adjacent the periphery of the mill ends and said studs locked to the mill ends by means of oppositely contacting nuts carried on said studs, as indicated by way of example in Fig. 1, at 20 and 21. Each mill end has a plurality of spaced peripheral and inwardly extending curved slots 22, the arc of each slot uses the point of rotation of a tie as a center, whereby when a tie is moved from the dotted line position in Fig. 4 to the full line position of said figure the pins 14 and 15 will move within the slots 22. To lock the tie against movement after a pin has been received within a slot 22, each pin 14 and 15 carries two nuts 24 and 25, the nut 24 being positioned for contact with the inner surface of the mill end, while the nut 25 contacts the beveled outer surface of the mill end adjacent slot 22, as is best shown in Fig. 3. A tightening of nut 25 will effectively lock the tie against swinging movement and its resultant dislocation of the studs from the slot or slots.

The rings of Fig. 6 are constructed to be in cross-section in the form of the frustum of a pyramid. In other words, the rings from the inner surface to the periphery thereof have tapered sides. This is also illustrated in Fig. 3, the inner surface of the ring being of greatest width. Said rings are provided with a plurality of equidistantly spaced apart transverse curved grooves 26; the curvature of said grooves corresponds to the curvature of the flange or tongue 18. In order to properly space the rings apart when it is intended to assemble them into drum form, I have provided the shims shown in Fig. 5 and designated as 27. The side shims include two spaced apart end members 28 and 29, with interconnecting spaced pieces 30 and 31. This construction provides a way between members 30 and 31, and in the plane of the way, the ends 28 and 29 are both curvedly grooved, as shown at 32 and 33. It is intended that the shims should straddle the rings transversely thereof and at the zone of the transverse grooves 26, the curvature of the grooves 32 and 33 corresponding to the depth of the grooves 26 of the ring, while connecting pieces 30 and 31 transversely overlie the ring on opposite sides of a groove 26.

In assembling the rings so as to form a drum of a definite size, one mill end is secured to the shaft 4, whereupon the shaft is placed in a vertical position. The selected number of ties 12 may be secured to the mill end, with each tie swung to the open position shown in dotted lines at 23 in Fig. 4. The rings 3 are then assembled, one on top of the other, with the shims of proper thickness positioned adjacent the grooves 26 of alternate rings, so that a stack of spaced rings is provided. After a selected number of rings has been assembled the opposite mill end may be brought into position and the ties secured to said end through the medium of the stud 13 and nuts 20 and 21 carried thereby. To assure that all of the grooves 26 of the rings are in alignment and maintained in such alignment, one of the ties may be swung so that the tongue of

flange 18 may enter grooves 32 and 33 of the shims, and likewise align grooves 26 in the rings. This tie may be tightened by turning the nuts 24 and 25. Thereafter the other ties may be 5 swung into position, so that the tongue or flange 18 thereof will enter the ring and shim grooves. The bolts 14 and 15 enter the curved grooves 22 of the mill ends in every instance. After 10 assemblage of the rings between the mill ends, the drum may be lowered to a horizontal position and the shaft 4 positioned in the bearing blocks 5 and 6. The mill ends are provided with hubs which extend outwardly from the outer faces thereof. The hubs form castings together with the mill ends, each hub provided with diametric lugs, as for instance illustrated in Fig. 2 at 100 and 101, and which lugs are thereafter split up to the outer face of the mill end. The lugs are transversely bored so as to permit passage of bolts 102 therethrough, the bolts carrying the usual nuts 103. The actual bore of the hub is slightly greater than the diameter of the shaft. Thus after the mill ends have been placed on the shaft with the ties secured therebetween, the mill ends are capable of relative adjustment. By tightening the nuts 103 the lugs 100 and 101 are drawn together so that the hub 15 tightly engages the shaft. It is a simple matter to place a mill end of the construction stated 20 on a shaft and move it on said shaft prior to a tightening of the split hub. After the required spacing has been determined for the mill ends, the ties may be tightened so that movement thereof is prevented by tightening the nuts 20 and 21; 24 and 25. The mill end 2 carries a pulley or wheel 34, and it is intended that a belt, 25 chain or other device shall have contact with this wheel and with a motor, whereby the drum may be rotated. Adapted to surround the drum and spaced from the periphery thereof, is a casing 35. This casing is in two parts, the two parts being 30 hinged at 36, whereby the part 37 may be lifted upwardly for inspection of the drum or for other purposes. The casing 35 has an inclined portion at 38, whereby when the drum is in operation and grinding ore the fines will be projected against the casing and directed outwardly in the direction of the arrow 39 to permit recovery of the fines. The casing 35 is provided with flanged 35 ends 40 for confining the fines within the casing. This casing is held to the supporting structure 7 in any convenient manner. For instance, the hinge pin 41 for the hinge extends between extensions 42 and 43 carried on the supports 7 and 9.

The operation, uses and advantages of the invention are as follows: We assume that the rings have been properly assembled and locked by the ties. These ties not only draw the rings 60 closely together, so that every ring will be spaced in accordance with the shim thickness, but assure that no sag occurs in the drum during actual use of the drum in the grinding of the ore. By providing each tie with means for locking the 65 tie at its ends to the mill ends, the ties are prevented from moving and the webs 19 prevent any bending movement in the plane of the flange 18. Thus all of the rings are maintained in alignment and the centers thereof all lie on the 70 same axis.

The inventors are aware that certain prior devices incorporate rings through which fines are directed, but so far as the inventors are aware no means has been provided of the simple character of the present invention for preventing sag

in the drum structure when the drum is partially filled with ore to be ground. As has previously been pointed out, rollers are utilized within the drum, these rollers being of considerable weight and extending substantially the width of the drum. Rollers of this character, particularly when engaging ore to be ground, often cause sag in the drum structure, particularly centrally of the drum structure. If sag occurs then the fines will vary as to particle size, due to the fact that the rings are pressed closer together at certain points of their periphery than at other points. When it becomes necessary to replace rings or shims it is a simple matter to release the ties, one at a time, and thereafter separate the mill ends and replace the ring or rings with their shims. Due to the fact that the rings have tapered sides the fines are not liable to be held between the rings. Inspection of the drum is readily allowed by lifting the casing portion 37 upwardly, and minor adjustments can be made as may be necessary, such as, for instance, tightening of the bolts 24 and 25, or 20 and 21, for the ties.

In the practice of a mill of the character shown the ore enters the hollow shaft 4 at 45. This may be a dry or wet process, and the ore is received in the drum to be acted upon by the heavy rollers therein.

While it is not essential to the present invention, it may be mentioned that the present device incorporates a screenless, quick precision, continuous non-slime, peripheral pulp discharge, eliminating classification for return of oversize, providing direct grinding action without loss of motion. It should also be mentioned that in the operation of a mill of this type best results are obtained by first reducing the ore in a rock crusher to size, probably half-inch or less, whereby quick grinding action and maximum capacity output can be had in the mill. It should also be mentioned, although the drawing does not show construction and it does not form a part of the present invention, that shaft 4 is usually provided with a series of transverse perforations through which the ore entering the shaft is discharged into the drum in order to distribute the ore properly. Also the shaft inward from bearing 5 is capped or closed to prevent passage of the ore completely through the shaft.

We claim:

1. A drum structure for a ring and roll mill including two spaced ends, a plurality of rings positioned between said ends, and circumferentially spaced ties extending between and swingingly mounted on the ends for releasable engagement with the rings for holding the rings in working relationship; each tie provided with a flange for transverse peripheral engagement with the rings to center the rings against relative radial shifting when all of the tie flanges engage the rings.

2. A drum structure for a ring and roll mill including a pair of mill ends, grinding rings positioned in axial alignment between said mill ends, and spaced ties transversely positioned between

the mill ends for locking the mill ends and said rings in working relationship; each tie provided with means whereby the tie is swingingly mounted on the pair of mill ends; all ties provided with means for engagement with the grinding rings when the ties are swung to one position between the mill ends for maintaining the grinding rings on a common axis.

3. A drum structure for a ring and roll mill including a pair of spaced apart mill ends, ties extending between said mill ends and mounted thereon for radial swinging movement inwardly of the mill ends or outwardly thereof, a plurality of grinding rings positioned between the mill ends and inwardly of the ties, said ties engaging the rings when said ties are radially swung inwardly of the mill ends, and means whereby the ties are locked against movement when the said ties are engaging said rings to position said rings on a common axis.

4. A drum structure for a ring and roll mill including a pair of mill ends and a shaft upon which said mill ends are mounted, spaced ties secured between and on the mill ends, each tie provided with means for swingingly mounting the same between the mill ends, a plurality of grinding rings positioned between the mill ends, and each tie provided with an elongated flange adapted to contact the periphery of the rings when said tie is swung inwardly of the mill ends, for holding all of said rings on a common axis.

5. A drum structure for a ring and roll mill including a pair of mill ends, a plurality of grinding rings between said mill ends, each grinding ring provided with a spaced peripheral series of transverse grooves and ties transversely extending between the mill ends and mounted thereon for locking the mill ends and the said rings in working relationship, said ties including a transverse rib adapted to enter the grooves of said rings for holding the said rings on a common axis, and web members for each tie in the plane of the rib for transversely supporting the rings and preventing bending movement in the tie.
